UNITED STATES PATENT OFFICE.

JOSEPH BORSOS, OF COLUMBUS, OHIO.

SAFETY-ENVELOP.

1,185,469.

Specification of Letters Patent. Patented May 30, 1916.

Application filed March 20, 1916. Serial No. 85,477.

To all whom it may concern:

Be it known that I, JOSEPH BORSOS, a subject of the King of Hungary, residing at Columbus, in the county of Franklin and 5 State of Ohio, have invented certain new and useful Improvements in Safety-Envelops, of which the following is a specification.

This invention relates to certain new and 10 useful improvements in safety envelops.

An object of the invention is to provide a safety envelop formed of a blank including enfolding sections that are interlocked and gummed so that it will be impossible for unauthorized persons to gain access to the contents thereof without in some manner injuring the envelop or indicating that the same 15 has been tampered with.

With these general objects in view and 20 others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—Figure 1 is 30 a plan view of the envelop blank constructed in accordance with the present invention. Fig. 2 is a plan view of the same with the lower blank section and one of the side flaps folded inwardly. Fig. 3 is a plan view of 35 the envelop with both side flaps folded inwardly, with the slots in the side flaps superposed. Fig. 4 is a plan view of the envelop with the sealing flap carried by the lower blank section interlocked and gummed to the 40 side flaps. Fig. 5 is a plan view of the envelop in completely closed position. Fig. 6 is a vertical cross-sectional view taken on line VI—VI of Fig. 4, with the sealing flap moved to an angular position, and, Fig. 7 is 45 a vertical sectional view taken on line VII—VII of Fig. 5, showing the position of the sealing flap tongue when the envelop is in completely closed condition.

Referring more in detail to the accompanying drawing, the reference numeral 10 designates the main body-portion of the envelop blank which constitutes the front wall of the envelop while a lower blank section 11 is carried thereby and forms the rear wall 55 of the envelop. Side flaps 12 and 13 are carried by the ends of the body-portion 10 and

are preferably of the configuration shown in plan view in Fig. 1, each side flap being slotted as at 14 with the slots so positioned that when the side flaps are folded inwardly 60 in overlapping relation and superposed relative to the body-portion 10, the said slots will register as indicated in Figs. 3, 6 and 7.

A substantially triangular extension 15 is carried by the outer edge of the lower blank 65 section 11 and is provided at the outer end thereof with a sealing tongue 16, the inner face of which is gummed as at 17 while the rear face thereof is gummed as at 18 as indicated in Fig. 3. A folding cover flap 19 70 is carried by the opposite side of the body blank 10 and is provided at the outer end thereof with a gummed sealing tongue 20.

In order to fold the envelop blank shown in Fig. 1 to the position shown in Figs. 5 75 and 6, the lower blank section 11 is folded upwardly on the creased line —a— to cause the blank sections 10 and 11 to lie juxtaposed, and after which the side flap 12 is folded inwardly on the line —b— as shown 80 in Fig. 2. The opposite side flap 13 is then folded inwardly on the creased line —c— to cause the slotted openings 14 in the side flaps 12 and 13 to register as indicated in Fig. 3. The lower curved edges of the side 85 flaps 12 and 13 are gummed as at 21 for adhesively engaging the blank bottom section 11. By folding the triangular extension 15 carried by the lower blank section 11 on the creased line —d—, the gummed surface 18 90 of the tongue 16 is caused to adhesively engage the outer face of the side flap 13 while the end of the tongue passes through the registering slots 14 in the side flaps and has the gummed portion 17 thereof adhered to 95 the inner side of the side flap 12 as indicated in Fig. 6. In this position, the matter to be inserted into the envelop may at this time be introduced and the cover flap section 19 folded on the line —e— to bring the gummed 100 section 22 into adhesive engagement with the side flaps 12 and 13. The gummed tongue 20 is then passed upwardly beneath the lower edges of the side flaps 12 and 13 to a position to lie between the side flaps and the 105 lower blank section 11 as is indicated in Fig. 7 and to be gummed at this point to the said side flaps.

From the above detailed description of the invention, it is thought that the construction and operation thereof will be readily apparent, and while the form of the inven-

tion herein shown and described is what is believed to be the preferred embodiment thereof, it is nevertheless to be understood that various forms, modifications and arrangements of the parts may be made without departing from the spirit and scope of the invention as claimed.

What I claim as new is:—

- 10 An envelop formed of a blank including a main body portion, side flaps carried thereby and having slotted openings adjacent to their ends and arranged to register when the flaps are folded inwardly, the lower edges of the flaps having curved gummed edges and
- 15 the portions having the slots being of substantially rectangular contour, a lower blank section carried by the main body-portion

and having a substantially triangular extension having a gummed terminal, a folding cover flap carried by the main body-portion 20 and having a substantially semi-circular contour and a rectangular extension, the extension and the edges of the sealing tongue being gummed, the gummed tongue carried by the triangular extension being adapted to be 25 inserted in the registering slots of the side flaps, and the gummed tongue carried by the cover flap being adapted to be moved to a position between the lower blank section and the side flaps and be gummed to the 30 latter.

In testimony whereof I affix my signature.

JOSEPH BORSOS.
